UNITED STATES PATENT OFFICE

2,473,881

HIGH-FREQUENCY DIELECTRIC HEATING APPARATUS

Richard H. Hagopian, Halethorpe, Md., assignor to Westinghouse Electric Corporation, East Pittsburgh, Pa., a corporation of Pennsylvania

Application June 25, 1946, Serial No. 679,078

4 Claims. (Cl. 219—47)

1

This invention relates to the dielectric heating of articles or substances of irregular shape or composition, or both, which are moved by a conveyor through a rapidly alternating electric field. Generally such work or charges are difficult to heat in a uniform or desired manner when the alternating electric field is such as is established solely by a single pair of spaced oppositely charged electrodes; although in some circumstances rotating the work as it moves through the field helps to produce a more uniform heat-treatment.

An object of my invention is to provide a dielectric heating system of a type described for controllably heating pieces of work of a type described as they move through an alternating electric field.

A further object of my invention is to provide a dielectric heating means of high productive capacity.

A further object of my invention is to provide a dielectric heating system which comprises a conveyor for moving the work through an electric field which is established between spaced, outer, or principal, electrodes; the system having means for insuring a more uniform or more desirable heat-treatment of the work without necessarily requiring that the work be rotated while in the electric field.

Features, objects and innovations of my invention, in addition to the foregoing, will be discernible from the following simplified disclosure of a preferred form to which, however, I am not limited. This disclosure, disclosing the principles of my invention, comprises the following description and drawing which are to be considered in conjunction. In the drawing:

Figures 1 and 2 are diagrammatic, elevational and plan views, respectively, of an arrangement in accordance with my invention.

Referring to the drawing, a charge or work-receiving conveyor is illustrated as an endless belt 1 driven by any suitable driving means 2. The belt may be moved either step-by-step or continuously as is known in the art. Preferably the belt is of insulating material and has a plurality of spaced heating stations 3, each comprising a work-holding means shown as a low pedestal 4 attached to the belt. As each pedestal moves past a loading point A, it receives a piece of work 5 to be dielectrically heat-treated. Preferably,

2

means are provided on the pedestal for centering or setting the work in a predetermined position on it. The moving belt carries the work through an electric field to an unloading point B where the work is dumped or otherwise removed from the pedestal.

In the embodiment described, the dielectric field in which the pieces of work to be heat-treated are immersed, is initially established between, and bounded by, principal electrode-means in the form of two stationary elongated flat parallel plate-electrodes 7 and 8. A high frequency tube-oscillator generator 9, suitably connected to the plate-electrodes, supplies the heating energy. The drawing schematically shows the generator connected across the plate-electrodes through a conductor 10 and ground connections 11. However, it is understood that, in practice, the connections may comprise a high frequency coaxial transmission line with an outer conductor grounded, or some equivalent means; and some means may be utilized if necessary, to smooth out or render ineffective any voltage wave-pattern that might otherwise tend to exist along the plate-electrodes.

Ordinarily, with nothing in the space between the plate-electrodes, the electric field across the space would be of uniform gradient. The field lines will be disturbed when a substance is introduced into the field, but the change is usually not such as to produce the heating desired in the substance. A distinct feature of my invention resides in shaping the field lines so that they will penetrate the substance, or work, in a manner to controllably heat-treat the work. To this end, each heating station 3 on the belt is provided with inner or auxiliary electrode-means which are relatively fixed with respect to the pedestal and, hence, the moving work, but which shape the field lines heating the work as it passes through the electric field. These auxiliary electrodes are preferably highly conducting so as to create curved equi-potential surfaces in spots about the work being heat-treated. As shown in the drawing, these electrodes comprise a plurality of pairs of thin curved electrodes 13 and 14, each such electrode being disposed between a plate-electrode and the facing side of a piece of work. These auxiliary electrodes are spaced from the work and do not completely surround it. They

may be narrow pieces of metal which are solid, foraminous, or otherwise perforated. Or they may be any other field distributing material which, preferably, does not absorb much energy from the rapidly pulsating electric field.

The electrodes 13 and 14 are secured to the pedestals 4 and move therewith. Each auxiliary electrode is electrically free while passing between the plate-electrodes 7 and 8; by electrically free meaning that there is no electric connection to it so that it will assume a potential arising out of its particular position between the plate-electrodes 7 and 8. Being of metal, each auxiliary electrode will distort the field lines and establish an equi-potential surface wherever the metal of the electrode is located. The voltage or potential difference between the auxiliary electrodes 13 and 14 will be less than between the plate-electrodes 7 and 8.

The shape, size and number of auxiliary electrodes about each piece of work 3 will determine the concentration of the field lines at the different points where they penetrate the work for heating it. In other words, the field lines can be directed into the work in a desired manner determined by the number, shape and disposition of the selected auxiliary electrodes.

When the auxiliary electrodes 13 and 14 are out of the heating electric field, or as they pass out of the field, they may be grounded by engaging grounded circuits including resilient brushes 15.

It is obvious that my invention is subject to wide variation in application; and that I am not limited to the embodiment disclosed.

I claim as my invention:

1. A dielectric heating system comprising means for establishing a dielectric field, said means comprising a pair of spaced primary electrodes, a conveyor means having a plurality of spaced heating stations, said conveyor means successively progressing said stations between said primary electrodes, each of said stations comprising work-receiving means and auxiliary field-affecting electrode means secured to said conveyor means.

2. A system including that of claim 1 but characterized further by said auxiliary electrode-

means comprising a pair of insulated metal members, each of which is between said work-receiving means and one of said primary electrodes.

3. A dielectric heating system comprising means for establishing a dielectric field, said means comprising a pair of spaced upright primary electrodes, a conveyor means having a plurality of spaced heating stations, said conveyor means successively progressing said stations between said primary electrodes, each of said stations comprising means for receiving work and a pair of insulated metal members, each of said metal members being between said work-receiving means and one of said primary electrodes, said metal members being attached to said conveyor means and extending upwardly.

4. A dielectric heating system comprising means for producing a dielectric heating field, said means comprising a pair of spaced upright primary electrodes adapted to have field lines established therebetween, a conveyor means having a horizontal portion provided with a work-treating station for carrying work through the space between said upright primary electrodes, said heating station on said conveyor comprising a work-receiving means and auxiliary electrode means secured to said conveyor-portion and movable therewith for determining the concentration of said lines that penetrate the work on said heating station as the work travels therewith through the space between said primary electrodes.
